DESIGN FOR A NEWSPAPER VENDING MACHINE

George T. Hemmeter, Berkeley, Calif.

Application December 8, 1945, Serial No. 124,553

Term of patent 14 years

(Cl. D52—3)

To all whom it may concern:

Be it known that I, George T. Hemmeter, a citizen of the United States, residing in the city of Berkeley, county of Alameda, State of California, have invented a new, original, and ornamental Design for Newspaper Vending Machine, of which the following is a specification, reference being had to the accompanying drawing, forming part thereof.

Fig. 1 is a perspective view of the front of a newspaper vending machine, showing my new design.

Fig. 2 is a rear perspective view of the newspaper vending machine shown in Fig. 1.

I claim:

The ornamental design for a newspaper vending machine, substantially as shown.

GEORGE T. HEMMETER.
